UNITED STATES PATENT OFFICE.

CHARLES W. LOUIS, OF SPRINGFIELD, MASSACHUSETTS; ASSIGNOR TO EDWARD R. BUCK,
OF WINDSOR, VERMONT.

AUTOMATIC MAGAZINE-FIREARM.

No. 900,865.

Specification of Letters Patent.

Patented Oct. 13, 1908.

Application filed March 21, 1907. Serial No. 363,568.

To all whom it may concern:

Be it known that I, CHARLES W. LOUIS, a citizen of the United States of America, residing at Springfield, in the county of Hampden and State of Massachusetts, have invented a new and useful Automatic Magazine-Firearm, of which the following is a specification.

My invention relates to improvements in magazine side firearms in which, when the arm is fired the recoil automatically reloads the same and resets the firing mechanism, and consists of the new and novel features of construction and combinations and arrangements of parts, severally and collectively, as hereinafter set forth.

The objects of my invention are, first, to produce an automatic repeating firearm which is capable of being utilized as a single-loader, and which when used as a magazine arm can be fired with great rapidity and can be speedily supplied with a new lot of cartridges when those in the magazine become exhausted; second, to produce an arm which automatically extracts and ejects the empty cartridge shell at the time the recoil forces back the breech mechanism for the entrance into the receiving- and firing-chambers of a fresh cartridge, so that the arm automatically extracts, ejects, reloads and resets for firing, after the first shot has been fired and so long as the supply of cartridges in the magazine holds out, as often and as fast as the trigger is pulled; third, to produce a fire-arm, of the class specified, which while being compact and exceedingly simple in construction and operation is strong, durable, reliable, convenient and safe—which is, in short, practicable and efficient in all particulars; fourth, to produce an arm of this kind with few parts which parts can be readily and quickly assembled and taken apart, and, fifth, to produce an arm into the construction of which no screws need to enter, thereby greatly simplifying the same and reducing the cost of manufacture.

Other objects and advantages will appear during the course of the following description.

Although the said invention relates particularly to side arms or pistols, I desire to include within the scope of the same the application of so much of my improved mechanism as is suitable for other kinds of fire-arms, and do not wish to be limited or re-

stricted to pistols wherever any of the novel features have a wider range of application and adaptability.

I attain the aforesaid objects by the means and mechanism illustrated in the accompanying drawings, in which—

Figure 1 is a side elevation of the frame of the improved pistol, including the receiver at the butt end, the barrel, the fore-stock, and the handle; Figs. 2, 3 and 4, side, end and bottom views, respectively, of the receiver and fore-stock slide or cover; Figs. 5 and 6, side and end views, respectively, of the lock-chamber cover; Fig. 7, a longitudinal vertical section through the pistol and the assembled parts which enter into its construction, the magazine being full and the operating or firing mechanism being normally or initially disposed as it appears before the first shot is fired, or as it would appear for the fraction of a second after the firing of a shot except that when there would be a cartridge shell in the firing-chamber; Fig. 8, a transverse vertical section through the receiver and handle, the operating or firing mechanism, or so much of it as appears, standing as shown in the preceding view; Fig. 9, a rear edge view of the upper part of the cartridge case or magazine proper; Figs. 10 and 11, side and end views, respectively, of the combined guide and locking rod; Figs. 12, 13, 14 and 15, plan, front end, side and rear end views, respectively, of the bolt; Figs. 16, 17 and 18, plan, side and rear end views, respectively, of the firing-pin; Figs. 19 and 20, side and end views, respectively, of the tubular plunger which affords a bearing or abutment for one end of the firing-pin spring and is utilized in manually setting the firing mechanism; Fig. 21, a section of the pistol showing the arrangement or disposition of parts at the instant a cartridge rises from the magazine into the receiving-chamber in the rear of the firing-chamber; Fig. 22, a detail sectional view of the extractor and ejector with associated parts, showing them in position to act on a shell; Fig. 23, a similar view to the preceding one, showing the positions of the extractor and ejector, with co-acting members, after they have done their work and the shell has been expelled from the pistol; Fig. 24, a plan view of the ejector; Fig. 25, a sectional view of the frame and side elevation of the interior members, the operating or firing

mechanism being in readiness to discharge the cartridge in the firing-chamber upon pulling the trigger, it being first necessary, however, to release the latter from the safety-
5 catch which is here shown in its operative position; Figs. 26 and 27, edge and side views, respectively, of the combined abutment and locking block; Figs. 28, 29 and 30, top, side and back views, respectively, of the safety-catch; Figs. 31, 32 and 33, top front and side views, respectively, of one of the lock members; Figs. 34, 35 and 36, top, side and back views, respectively, of the other lock members, and Fig. 37, a side elevation of
10 the pistol complete.

Similar figures refer to similar parts throughout the several views.

Starting with a description of the frame and its appurtenances, the peculiar construction of which enables me not only to employ to the best advantage my improved operating mechanism, but also to dispense with many parts heretofore used and to avoid the use of screws, and having special reference 20 to the first six views and to Figs. 8 and 37 of the drawings, it will be observed that the receiver 1, barrel 2, fore-stock 3 and handle 4 are all comprised in one piece, and that four pieces only are required to close the 25 openings in such frame which it is desired to close or to otherwise complete the same, such pieces consisting of a plate or cover 5 for the lock-chamber 6, a plate, slide or cover 7 for the receiver and fore-stock, and two 30 grips 8 one on each side of the handle 4. The rear end of the bore 9 of the barrel is enlarged to form the usual firing-chamber 10, and behind this chamber is a cartridge receiving-chamber 11 which opens into, 35 being low and behind, a receiving-chamber 12 for the firing mechanism. The last-mentioned chamber is located partly in the receiver 1 and partly in the fore-stock 3 through the front end of which latter it opens.

40 The chamber 12 has a large opening in one side which is adapted to be closed with the cover 7, and in the side of the frame opposite this large opening is a smaller opening 13 into the chamber 11 through which the empty shells are ejected and cartridges are introduced when the arm is loaded singly by hand. The trigger pivot or pin 14 is located in the lock-chamber 6, behind which is a slot 15, and a recess 16 in 45 the permanent side wall of said chamber for a safety-catch 17 to operate in. A recess or pocket 18 is provided in the bottom of the chamber 6 for a trigger- or lock-spring 19. The edges of the open side of said chamber 50 6 are under-cut as indicated by dotted lines 20 to receive corresponding beveled parts 21 of the cover 5, whereby said cover is held securely in place. The top and bottom edges of the open side of the chamber 12 are under-
55 cut as indicated by dotted lines 22 to re-

ceive corresponding beveled parts 23 of the cover 7. A bead 24 along the top edge of the cover 5 receives and overlaps the adjacent portion of the lower edge of the cover 7 when the two covers are in position. The front terminal of the cover 7 is cut away on the inside at 25, so as to afford some resiliency at this point, leaving a lug 26 which is adapted to snap over two knobs or projections 27 on the frame properly located to 75 be engaged by said lug when said cover is slid into place with its front end in contact with the front edge of the side opening into the chamber 12, and to prevent the cover from being withdrawn from said frame without first forcing the thin terminal of the cover outward until said lug is able to clear said projections. An indentation 28 is made in the face of the fore-stock 3 to facilitate inserting the thumb for the purpose of prying the lug 26 out of engagement with the projections 27. The cover 5 is held securely against displacement by the cover 7, since said cover 5 can only be removed upwardly and this only after said cover 7 has been 80 unfastened and drawn to the rear sufficiently to clear the small cover. A slot 29 is provided in the forwardly-extending portion of the cover 7 for an ejector 30. The receiver is interiorly slotted at 31 for the said ejector, 85 and at 32 for the head of an extractor 33.

Within the receiver 1 and the handle 4, directly below the cartridge receiving-chamber 11, is a magazine-chamber 34 opening at the top into the chamber 12 and at the bottom 100 through the base of said handle. The walls of this magazine-chamber flare outwardly at the base and the sides of such chamber above the flaring parts are cut out leaving two upwardly-extending thin tongues 35 having 105 holes 36 therein and provided at their upper ends with outwardly-convex rolls or beads 37. On the outer faces of the handle 4 are longitudinal flanges 38 beneath which the longitudinal edges of the grips 8 are adapted 110 to fit. On the inner faces of the grips 8 are grooves arranged and adapted to receive the beads 37 of the tongues 35, when said grips are slipped into place beneath the flanges 38, whereby the grips are securely fastened to 115 the handle. The tongues 35 are more or less resilient and readily snap into engagement with the grips. By introducing a screw-driver or other suitable implement into the magazine-chamber 34 and the hole 36 in 120 either of the tongues 35, such tongue can be pried inward sufficiently to disengage its bead from the adjacent grip and thus permit the latter to be withdrawn from the confining flanges 38. A magazine-case 39 is 125 provided which is adapted to occupy the chamber 34 and the bases of the grips 8 are cut out at 40 to enable one to grasp such case when in said chamber. Side flanges 41 at the bottom of the magazine-case are counter- 130

sunk within the magazine-chamber when said case is in place, but are exposed through the openings 40, and afford convenient means for securing a firm grip on the case when it 5 is to be removed from its chamber.

Within the magazine-case 39 are the usual follower 42 and spring 43, here, however, the follower differs from others in that it has a longitudinal, central, convex part 44 having the same diameter as the major diameter of the cartridge for which the magazine is designed. The particular object in providing a convex follower instead of one of the ordinary kind is to make provision for locking the firing mechanism when the cartridges become exhausted, as will appear hereinafter. The sides of the magazine-case near the back are extended above the upper edges of said case and are curved inward so 10 that they together form a stop 45 against which the rim of the uppermost cartridge in the case or the corresponding part of the follower, in the absence of any cartridge, comes to rest and bears, until released if a 15 cartridge, or forced down if the follower. Since the cartridge to be released from the stop 45 is moved forward and then rises into the receiving-chamber 11, in the manner yet to be explained, it is necessary to notch the 20 front side of the case 39 at the top, as at 46, and the bottom of the firing-chamber 10, as at 47, for the passage of the bullet. See Figs. 7, 9, 21, 23 and 25. The magazine-case 25 is releasably held in the chamber 34 by means of a combined abutment and locking block 48 which has a hook 49 on its rear face adapted to pass through a suitable slot in the front of the handle 4 into engagement with said case, the arrangement being such that when 30 the case is inserted in the chamber and forced home it encounters said hook, causes said block to rock forward and then permits the block to return and insert its hook into a slot formed in the adjacent side of the case to 35 receive it. Before removing the magazine-case from its chamber it is necessary to manually operate the block 48 and withdraw the hook 49 from engagement with the case.

The combined abutment and locking block 50 constitutes the connecting link, as it were, between the active and non-active parts of the arm, or between the frame and the major portion at least of the removable members, and is a very important element in the structure. Said block, in addition to the hook 49, has a rounded head 50 at the top, a perforation 51 extending from front to back and upwardly-inclined, below said head, and two lateral ears 52 near the base. The head 50, 55 after passing through a slot 53 located between the handle 4 and the trigger-guard and through a suitable passage in front of the front wall of the magazine-chamber 34 and across the chamber 12, enters into engagement with a transversely grooved part

of the top of said chamber 12. The block is held with its head in the above-mentioned groove by means of a combined guide and locking rod 54 having a supporting rear extension 55 which enters the perforation 51. 70 The space provided in the frame for the body of the block is sufficient to enable said block to rock forward on its bearing head far enough for its hook not only to release the magazine-case but also to clear the adjacent 75 wall of the magazine-chamber. It is necessary to incline the perforation 51 to enable the block to be rocked on the extension 55 for the release and engagement of the magazine-case. The base of the block is below the 80 frame and the ears 52 are above such base on the outside of the frame. The ears serve as grips or handles for the finger or thumb or both of the operator.

I will proceed now to describe the operating or firing mechanism, which for present purposes I will divide into two main groups, namely, the bolt and firing-pin mechanism, and the trigger or lock mechanism. Intimately associated with the aforesaid groups 90 and forming in reality parts of the operating mechanism are the extractor, ejector and safety-catch already mentioned. In the first group are a striker or firing-pin 56 mounted at the back end of a slide 57 adapted to reciprocate on the bottom of the chamber 12, a breech-block or bolt 58 having a longitudinal passage therein for said firing-pin and mounted at the back end of a slide 59 adapted to reciprocate with and on said 100 slide 57, a tube or plunger 60, a main-spring 61, a firing-pin-spring 62, and the aforesaid rod 54. In the second group are a trigger 63 perforated at 64 for the pin 14, a detent 65 having its front end pivoted at 66 to the 105 corresponding end of said trigger, and the spring 19 pocketed in the fore-stock and arranged to bear against the front end of said detent just behind the pivot 66 from below.

As in the case of the frame and its appurtenances, the operating mechanism comprises an exceedingly small number of parts and screws are entirely absent therefrom.

At the closed front end of the firing-pin slide 57 is a slotted upstanding lug 67 which affords a bearing for the corresponding end of the spring 62 while at the same time providing a passage for the rod 54, and at the opposite end of said slide is a raised part which directly supports the firing-pin 56. 115 A little distance back from the front end of the slide 57 the bottom edges of the two bars forming the side-pieces or side-rails of said slide are notched to provide shoulders 68. The lug 67 is adapted to operate between the side-rails of the bolt slide 59. The closed front end 69 of the slide 59 which extends below the base of the side-rails has a hole 70 therein for the plunger 60. The bolt 58 is directly supported by the raised 120 125 130

part at the back end of the slide 59, such raised part being in advance of the corresponding part of the slide 57 when the members are assembled. Both slides are open at 5 their rear terminals to accommodate the upper portion of the magazine-case which rises between the side-rails of the slides.

Between the ends of the slide 59 is a web 71 connecting the side-rails of said slide and 10 extending down between the side-rails of the slide 57. In the front portion of the web 71 is a flange 72 which forms the front bearing for the spring 61. The web 71 is cored out for the plunger 60 and a spring 15 61 and has its sides notched near the back to provide two pairs of shoulders 73 and 74. In one side of the bolt 58 are a slot 75 for the extractor 33, indentations 76 on both sides of said slot, and a chamfer 77 20 behind the slot, the indentations and chamfer being associated with the ejector 30 as will presently appear. The bolt 58 externally conforms to the shape of the cartridge receiving-chamber 11 and the upper rear 25 portion of the receiving chamber 12.

The plunger 60 consists of three lengths having the same number of diameters in cross-section, the largest diameter being at the front and the smallest at the rear. Within 30 in the front length of the plunger is a longitudinal passage 78 for a head 79 on the front end of the rod 54, and within the other two lengths is a longitudinal passage 80 for the spring 62. The head 79 just fits 35 the passage 78, and the front end of the plunger is perforated at 81 to provide for the escape of air when said plunger moves rearward. A slot 82 in the bottom of the plunger is arranged to admit the firing-pin 40 lug 67, between which and the inturned back end of the plunger the spring 62 bears. The aforesaid inturned end of the plunger is adapted to fit the enlarged part of the rod 54, said rod between its extremities having a 45 major and a minor diameter. A pin 83 extends inward from the middle length of the plunger adjacent the junction of such length with the front length. On the rear terminal of the rod 54 in front of the extension 55 is 50 a rectangular flange 84 adapted to be received between the side-rails of the bolt and firing-pin slides and to bear against the front face of the block 48. The spring 61 bears between the flanges 72 and 84. A longitudinal slot 85 is cut in the head 79 of the rod, such slot being large enough for the passage of the pin 83. The arrangement of parts is such that, when they are assembled 55 with the rod in the center, the spring 62 60 around said rod, the plunger outside of said spring and rod, the spring 61 around the inner length of said plunger and the rod, and all within the slides except the front terminal of the plunger, the center of the slot 85 is 65 in the same plane with one of the diagonals

of the flange 84 while the axis of the pin 83 and the center of the slot 82 which receives the lug 67 are in the same plane with two of the sides of said flange; this brings said pin 83 always behind the shoulder formed 70 at the junction of the rod with its head 79 and prevents the separation of the parts. The said parts can be readily unlocked, however, by first forcing the firing-pin, against the resiliency of its spring, entirely out of 75 the bolt and removing the lug 67 from the plunger, and then turning the plunger to bring the slot 85 into line with the pin 83, now the rod and plunger can be separated, the spring 61 is left free for removal from 80 the web 71, the plunger can be drawn out of said web and the lug 69, and the spring 62 taken from the plunger through the slot 82. The extractor 33 is pivoted at 86 to the 85 bolt 58 and lies with its tail in the slot 75 and its head extending in front of said bolt ready to snap over the rim of a cartridge shell in the usual manner, said tail being thin at its rear end and affording the necessary amount of resiliency for the extractor. 90 This extractor does not differ materially from other similar devices.

The ejector 30 is a forked piece with two dogs 87 on its inner face arranged and adapted to be received into the indentations 95 76 in the bolt when the latter is retracted, and with a dog 88 also on its inner face at the back end arranged and adapted to be acted upon by the chamfered part 77 of said bolt when retracted. The head of the ejector is 100 pivoted at 89 to the cover 7. The head of the extractor 33 projects outward between the forks of the ejector 30 and moves back and forth therebetween as the bolt reciprocates. When the bolt is forward the head of 105 the ejector projects beyond the front ends of the ejector forks into the slot 32. The ejector is in the slots 29 and 31 with the parts which deliver the blow to the shell located 110 opposite the opening 13.

The trigger 63 is bifurcated above the tail or finger piece, as clearly appears at 90 in Figs. 31 and 32, and the detent 65 operates in the space thus formed. A cross-piece at the front end of the trigger 63 is provided 115 on top with two dogs 91 which are the direct engaging and releasing members for the firing-pin slide shoulder 68. At the back of the trigger are two safety stops 92. A slot 93 is cut in the detent 63 into which the pin 14 120 is received, and the bottom of said slot limits the upward swing of the detent. The front ends of the trigger and detent are pivoted together as already noted. At the back of the detent is a cross-piece having two dogs 125 94 on the top to engage and release the bolt slide shoulders 73 and 74 at the proper time. Behind and below the dogs 94 is a hook 95. It will now be seen that the spring 19 bearing as it does on the detent 65 between the

pin 14 and the pivot 66 constantly tends to force upward the front of the trigger 63, also to force upward the back of said detent; furthermore, that both the trigger and detent 5 rock on said pin, the arrangement being such that the edge or edges of the slots 93 always bear at some point on the pin.

The safety-catch 17 is provided with a hook 96 adapted for engagement with and 10 disengagement from the detent hook 95, with two feet 97 capable of holding down the trigger stops 92, and with a finger-piece 98 for actuating the catch into and out of locking contact with the trigger. The finger-piece 98, which in practice projects on the 15 right-hand side of the pistol, is connected with the body of the safety-catch by means of an angular arm 99 slidingly mounted partly in the frame slot 15 and partly in the 20 frame recess 16. Said finger-piece is of such size and shape that it can be passed through the slot 15 from the inside of the frame when the safety-catch is placed in position. The removal of the safety-catch from the lock-chamber 6 is effected by simply drawing the 25 finger-piece inward through the slot 15. The safety-catch might easily be made, without changing any essential feature, so that it could be introduced and removed from the 30 right-hand side of the frame.

Having now described the several elements which enter into my invention and explained somewhat in detail their relation one with another, I will next proceed to explain fully 35 the manner in which the parts are assembled into a complete arm, and will then describe carefully the operation of the mechanism from start to finish. The manner in which the parts are separated again after being assembled will generally be understood from the description of the assembling, but wherever necessary special information is herein given on this subject.

Starting with the bare and empty frame shown in Fig. 1, the safety-catch 17 may first be placed in position in the lock-chamber 6 by passing the finger-piece 98 through the slot 15 thus locating the angular arm 99 in said slot and in the recess 16. The trigger 50 63 with its detent 65 is next mounted on the pin 14. The lock-spring 19 may be inserted at this time, or later after the other members have been introduced, as desired. The lock mechanism assists in retaining the safety-catch in place.

Before introducing the firing-pin and bolt mechanism it is assembled as follows: Insert the spring 62 in the plunger 60 through the slot 82, pass said plunger through the hole 60 70 in the end 69 of the slide 59, insert the spring 61 in the web 71, pass the rod 54 through said spring 61 into the plunger and through said spring 62, turning the plunger if necessary so as to permit the head 79 to 65 pass the pin 83 and then turning the plunger

to bring its slot 82 at the bottom, which action will carry the slot 85 by said pin and lock the parts together, compress the spring 62 with the fingers sufficiently to allow the lug 67 to be inserted in the slot 82 ahead of said spring, draw back the slide 57 until the firing-pin 56 can be elevated into line with the passage for the same in the bolt 58, and finally release said slide permitting said firing-pin to pass into said bolt under the influence of the spring 62. The angular flange 84 is now between the side-rails of the two slides where it is free to move lengthwise of the passage containing the same, but unable to turn therein. This mechanism is introduced into the chamber 12 through the side opening in the frame and pushed forward until the bolt with the firing-pin is in the cartridge receiving-chamber and said bolt or the vertical parts of the slide below the same come to rest against the adjacent end of that portion of the frame which separates the firing-chamber 10 from the chamber 12 below. The end of the plunger which projects beyond the fore-stock 3 is now grasped and the plunger drawn outward carrying with it the rod 54 against the resiliency of the main-spring, far enough to enable the abutment block 48 to be passed upward through the slot 53, the locking-chamber 6 and the space between the side-rails of the slides until its head 50 is socketed in the groove above. Immediately the plunger is released and the main-spring carries the flange 84 against the abutment block while the extension 55 enters the slanting hole 51, thereby securing such block and pressing it against the front wall of the magazine-chamber without, however, preventing the same from being swung forward to a limited extent upon the application of enough force to overcome the resistance of the main-spring. The block is, of course, supported at the top against the force of the main-spring by reason of its engagement with the roof of the chamber 12 and with the extension 55. The removal of the aforesaid mechanism is effected after releasing the abutment block from the rod extension 55 and withdrawing said block from the frame. The tendency of the springs is to keep the front end of the web 71 and the shoulder or flange 100 on the plunger in contact with each other so that in practice the bolt and plunger always move together. Lastly the cover 5 is slipped into place from above over the lock-chamber to assist in keeping the lock in position and to inclose the same, and the cover 7 is slid into the open side of the frame from behind to shut in the mechanism in the chamber 12, the lug 26 closing over the projections 27 and thereby locking said cover 7 which in turn secures said cover 5. See Fig. 37. The ejector 30 is brought into operative relation

with the bolt by the placing and closing of the cover 7.

When the magazine-case 39 is pushed into its chamber it first forces the hook 49 out of its path, rocking the abutment and locking block 48 forward against the resiliency of the main-spring, and then at the end of its upward travel receives said hook into locking engagement therewith. Before removing the magazine-case the locking block is grasped by its ears 52 and rocked forward enough to withdraw its hook from engagement with said case, then the case can be drawn out of the bottom of the handle 4. The magazine-case is filled in the usual manner and the cartridges are retained therein by the stop 45 over the rim of the uppermost cartridge, but when said case is inserted in its chamber with the upper portion just below the field of action of the bolt and between the bifurcated parts of both bolt and firing-pin and the bolt is forward the aforesaid cartridge encounters the latter before the case reaches its highest point and the cartridges are consequently correspondingly forced down against the resiliency of the spring 43, or rather held down while the case continues to rise and to carry said stop above and away from the first cartridge. Assuming that the arm is complete, is provided with a magazine-case containing cartridges, and has its safety-catch pushed back out of the way of the lock, and that the operating mechanism is disposed as shown in Fig. 7, the operation of such mechanism is as follows: Taking hold of the exposed terminal of the plunger 60 force it backward, by so doing the main-spring 61 is compressed between the flanges 72 and 84 and the bolt and firing-pin members are all carried toward the rear owing to the engagement of the shoulder 100 with the web 71. When the bolt clears the cartridge below said cartridge rises against the stop 45, thereby taking position in the path of the bolt upon its return. The plunger is released and the main-spring causes the bolt to advance and drive the top cartridge into the firing-chamber, the operation or movement of this cartridge being the same as that of the second cartridge, which will be hereinafter described in detail, and of every other cartridge in the magazine. Although the bolt has been permitted to assume its most advanced position, the firing-pin has been held back by the dogs 91 which meanwhile have been thrust into the path of the shoulders 68 by the action of the lock-spring and have engaged said shoulders. When the trigger is pulled the dogs 91 release the shoulders 68 and the spring 62 drives forward the firing-pin to explode the first cartridge. Instantly the recoil acts to retract both bolt and firing-pin and, before the trigger is wholly released by the finger of the operator or while in the

act of being released, the second cartridge is guided into the firing-chamber, the operation being described below. Several independent, however rapid, steps or separate and distinct actions occur at this time: First, 70 the detent dogs 94 which had been in the path of the rear edges of the shouldered parts of the web 71 and had been ridden down by such parts when the slide 59 moved backward and so caused said detent to swing 75 downward on the pivot 66 against the force of the spring 19, rise in front of the shoulders 73 as soon as the notched parts of said web arrive over said dogs, said spring then swinging the detent upward, and said 80 shoulders momentarily contact with the dogs as said slide commences to move forward and thereby check the slide long enough for the cartridge in the open end of the magazine to rise against the stop 45; second, the 85 dogs permit the shoulders to slip by them as the trigger begins to escape from the now relaxing finger of the operator and the slide advances again only to be once more checked this time by the shoulders 74 and the dogs, 90 and as the slide advances the bolt drives said cartridge forward until its rim clears said stop, then pauses while the cartridge rises into the receiving-chamber 11 (see Fig. 21); and, third, upon the complete release of the 95 trigger the shoulders pass over the dogs and said bolt drives the cartridge into the firing-chamber. All this takes place while the operator is releasing the trigger, without, however, calling for any unusual attention from him. Next, the pressure of the finger on the trigger having been removed, the lock-spring rocks the trigger and thrusts the dogs 91 in front of the shoulders 68 which immediately 100 engage therewith and lock the firing-pin. The trigger can now be pulled again to release the firing-pin to its spring, thus exploding the cartridge, or, if it is not desired to fire the arm until some subsequent time, the safety-catch 17 may be slid forward with its feet 97 over the trigger stops 92 and its hook 96 in engagement with the detent hook 95 (see Fig. 25). The hooks snap into and out of engagement against the resiliency of the lock-spring, and when in engagement retain the catch in such a position relative to the trigger that the latter can not be pulled. To unlock the trigger simply draw the safety-catch back out of engagement with the trigger proper and detent. 110

The operations above described are repeated every time the trigger is pulled until the last cartridge has been used, when the convex part 44 of the cartridge follower rises to the stop 45 in front of the bottom of the bolt at its last rebound and prevents further operation of the parts until the empty magazine-case has been moved, or a cartridge has been inserted by hand through the opening 13. 115

It should be noted, in passing, that the trigger when pulled draws down on the front or pivotal end of the detent while the spring 19 forces the main portion of the 5 detent forward as far as the pin 14 will permit, the detent rocking on said pin, except as it is depressed by the base of the web. 71. The working end of the detent is normally higher at the time the trigger is pulled than 10 while the trigger is free, unless such end is in contact with the web. The bolt is not released from the detent until the trigger is pulled, and the lock begins to take position to engage the firing-pin as soon as said lock 15 acts to release said bolt.

At the time the bolt seats a cartridge in the firing-chamber the head of the extractor 33 snaps over the rim of said cartridge or of its shell, and after the discharge when 20 the recoil takes place the extractor draws said shell out of said firing-chamber into the receiving-chamber 11. Immediately the chamfered part 77 of the bolt rides down the dog 88 and actuates the ejector 30 so 25 that it strikes the empty shell, drawn out by the extractor on top of the cartridge or elevator in the magazine below, a hammer blow and hurls it through the opening 13. The dogs 87 enter the indentations 76 in the 30 bolt at this time, and when said bolt advances the rear edges of said indentations contact with said dogs and actuate the ejector out of the chamber 11, leaving the ejector, however, with its dog 88 projecting 35 into the chamber 12 behind the bolt.

To recapitulate briefly--when the trigger is pulled and while in its "pulled" position the cartridge in the firing-chamber is exploded, the bolt and firing-pin recoil or 40 bound, the bolt members compress the main-spring, the empty shell is extracted and ejected, and said main-spring reasserts itself and advances the bolt with the fresh cartridge ahead of it, the last action occurring 45 at the instant the trigger is released. The firing-pin spring has not yet been compressed since it moved back with the rest of the firing mechanism, but upon the release of the trigger and the engagement thereby 50 of the firing-pin slide said spring, which is weaker than the main-spring, is compressed, owing to the fact that the front end of the weaker spring is now held by the lug 67 at a point further back than before while said 55 main-spring drives the plunger forward against the back end of the firing-pin spring into its original position. The release of the firing-pin spring when the trigger is again pulled brings about the restoration, 60 momentarily at least, of the firing-pin and its spring to normal or initial position, the same as the other firing mechanism members. The several operations incident to pulling the trigger take place with such rapidity 65 as to appear like a single action.

Cartridges may be inserted in the firing-chamber by hand through the opening 13, when the bolt is retracted, either when the magazine-chamber is empty or when there is a magazine-case therein, and an extra 70 cartridge can be introduced in this way above those in the magazine. When loaded through the opening 13, in the absence of the magazine case, the bolt and firing-pin will have to be retracted manually each time 75 through the medium of the plunger, as in making ready to fire the first shot from the magazine, but with the empty magazine-case present, after the first shot, the recoil can be utilized since the top of the follower will 80 stop the bolt and allow the cartridge to be inserted. The cartridge inserted under these circumstances presses the follower down out of the way of the bolt which latter immediately carries said cartridge into the firing- 85 chamber.

After a cartridge has entered the firing-chamber it and any and all cartridges in the magazine can be removed from the arm without firing, by setting the safety-catch 90 and manually reciprocating the plunger, a cartridge being ejected through the opening 13 each time said plunger is forced back until no more remain in the pistol.

The rear portion of the chamber 12 is here 95 shown as being practically air-tight, thus more or less of an air-cushion is provided for the bolt and firing-pin when driven back by the impact of the explosion. This prevents the shock which might otherwise be occasioned by the recoil.

It will be comprehended that the actions resulting from the explosion and the subsequent actions brought about by the main-spring all occur so quickly that by the time 105 the trigger is released to its spring a fresh cartridge has been introduced into the firing-chamber and the firing-pin is in position to be engaged and held by said trigger.

It should be observed that the block 48 110 constitutes an abutment for the main-spring which is normally fixed, and that the plunger affords an abutment for the firing-pin-spring which is movable.

This pistol is designed to use cartridges 115 the shells of which have rims of the same diameter as that of other portions of the shells in their largest parts, but so constructed, nevertheless as to provide room for the extractor head. The shoulder formed by 120 the front edge of the shell with the bullet inserted therein is the part that strikes and bears against the shoulder or flange at the junction of the firing-chamber with the bore proper in the barrel.

It is obvious that numerous structural changes and changes in the arrangement of the different members which enter into the ensemble of my firearm may be made, also many alterations in the shape and size of the 130

parts and of the firearm as a whole, and I do not wish to be restricted in these particulars; I desire and intend to include within the scope of my claims any and all modifications which 5 can be said to justly fall therein and seek to cover my invention broadly.

What I claim as my invention, and desire to secure by Letters Patent, is—

1. A recoil-operated firearm comprising a 10 frame, a spring-pressed slide having a bolt mounted above one end thereof, and a slide having a firing-pin mounted above one end thereof and operating through said bolt, said firing-pin slide being spring-pressed independent of the bolt.

2. A recoil-operated firearm, of the class described, comprising with the magazine a 15 spring-pressed slide provided with a bolt above one end and a spring-pressed slide 20 provided with a firing-pin above one end, said firing-pin operating through such bolt, the arrangement of parts being such that said bolt and firing-pin are driven back far enough by the force of the discharge to make 25 room for a fresh cartridge from said magazine.

3. In a recoil-operated firearm, of the class described, a spring-pressed bolt, a slide having a firing-pin at one end and a lug at the 30 other end, a hollow plunger, and a spring within such plunger between its inner end and the inside face of said firing-pin lug, the relation of said firing-pin to said bolt being such that the former is carried with 35 the latter when the latter is forced to the rear, said spring and plunger also being carried in the same direction at the same time.

4. In a recoil-operated firearm, of the class 40 described, a bolt, a firing-pin, a lock-pin, a trigger or lock device mounted on said pin, and a second trigger or lock device having its front end pivotally connected with the front end of said first-mentioned trigger or 45 lock device and cut away to receive said pin, said trigger or lock devices being provided with engaging and releasing members on opposite sides of the pin adapted to be operated alternately to act on said bolt and 50 firing-pin independently.

5. In a recoil-operated firearm of the class described, a bolt, a firing-pin, a lock-pin, a trigger or lock device mounted on said pin, and a second trigger or lock device having 55 its front end pivotally connected with the front end of said first-mentioned trigger or lock device and cut away to receive said pin, said trigger or lock devices being provided with engaging and releasing members on 60 opposite sides of the pin adapted to be operated alternately and to act on said bolt and firing-pin at different times.

6. In a firearm, of the class described, a 65 suitably mounted rod, a firing-pin spring

slidely mounted on such rod, a plunger 65 also slidely mounted on said rod and inclosing said spring, and a bolt spring encircling part of said plunger, said firing-pin spring having a bearing at one end against the end of the plunger which is within said 70 bolt spring, and the arrangement of parts being such that said springs act independently of each other.

7. In a firearm, of the class described, a 75 bolt spring, a normally fixed abutment for the inner end of such spring, a firing-pin spring, and a movable abutment extending for a portion of its length into said bolt spring, the end of said movable abutment which is in the bolt spring and adjacent to 80 said normally fixed abutment receiving the inner end of said firing-pin spring.

8. In a firearm, of the class described, a 85 slidely mounted bolt, an abutment, a spring between a bearing part of the bolt and said abutment, a plunger coacting with said bolt, a slidely-mounted firing-pin, and a spring between a bearing part of the firing-pin and a bearing part of the plunger.

9. In an automatic firearm, a slidely- 90 mounted bolt, an abutment, a spring between a bearing part of the bolt and said abutment, a plunger coacting with said bolt, a slidely-mounted firing-pin, a spring between a bearing part of the firing-pin and a 95 bearing part of the plunger, and supporting and guiding means for such members.

10. In an automatic firearm, a slidely- 100 mounted bolt, an abutment, a spring, a guide member pressed against said abutment by said spring, a plunger mounted on said guide member and coacting with the bolt, a slidely-mounted firing-pin, and a spring between a bearing part of the firing-pin and a bearing part of the plunger. 105

11. In an automatic firearm, a slidely- 110 mounted bolt, an abutment, a spring for said bolt, a guide member pressed against said abutment by said spring, a slotted plunger mounted on said guide member and coacting with the bolt, a slidely-mounted firing-pin having a bearing part for a spring extending into the plunger slot, and a spring in the plunger between said bearing part of the firing-pin and a bearing part of the plunger. 115

12. Firing mechanism, for an automatic 120 firearm, comprising a bolt having a slide member, a rod having a flange at one end and a head at the other, a spring between said flange and a bearing part of the bolt slide, a plunger mounted on said rod to coact with said bolt, and means to prevent the rod and plunger from being drawn apart except when abnormally disposed.

13. Firing mechanism, for an automatic 125 firearm, comprising a bolt and a firing-pin adapted to operate through such bolt, both having slide members, a rod having a flange

- at one end, a spring between said flange and a bearing part of the bolt slide, a plunger mounted on said rod to coact with said bolt, and a spring between a bearing part of the 5 firing-pin and a bearing part of the plunger.
14. Firing mechanism, for an automatic firearm, comprising a bolt and a firing-pin adapted to operate through such bolt, both having slide members, a rod having a flange 10 at one end, a spring between said flange and bearing part of the bolt slide, a plunger mounted on said rod to coact with said bolt, means to limit the outward movement of said plunger, and a spring between a bearing part 15 of the firing-pin slide and a bearing part of the plunger.
15. The combination, in an automatic firearm, of a frame having a chamber therein, an abutment member traversing such chamber, a slidably-mounted bolt having a slide in such chamber, a slidably-mounted firing-pin having a slide in such chamber, a spring between a bearing part of the bolt slide and said abutment member, a firing-pin spring, 20 and a bearing member for one end of said last-mentioned spring coacting with the bolt slide, the other end of the firing-pin spring bearing against a part of the firing-pin slide.
16. The combination, in an automatic fire- 30 arm, with a spring-pressed slide having a bolt mounted above one end thereof, and a spring-pressed slide having a firing-pin mounted above one end thereof and adapted to operate through such bolt, of a plunger 35 coacting with said bolt slide for manually retracting the bolt, and means to cause said firing-pin to be retracted with the bolt.
17. The combination, in an automatic fire- 40 arm, with a spring-pressed slide having a bolt mounted above one end thereof, a spring-pressed slide having a firing-pin mounted above one end thereof, and means to cause the slides with the bolt and firing- 45 pin to be retracted together and to be moved forward separately, of a plunger coacting with said bolt slide for manually retracting the bolt with said firing-pin.
18. The combination, in an automatic fire- 50 arm, with the firing mechanism including the main-spring, and a rod adapted to be held in place by said main-spring and having an extension, of a non-reciprocating displace- 55 able abutment block for the rear or inner end of said main-spring, such block being adapted to be held against displacement by said rod extension.
19. The combination, in an automatic fire- 60 arm, with the firing mechanism including the main-spring, and a rod adapted to be held in place by said main-spring and having an extension, of a non-reciprocating removable abutment member for the rear or inner end of said main-spring, such abutment member being adapted to be held against displacement by said rod extension.
20. The combination, in an automatic fire- 70 arm, with the firing mechanism including the main-spring, and a rod adapted to be held in place by said main-spring and having an extension, of a non-reciprocating displace- 75 able abutment block for the rear or inner end of said main-spring, such block being adapted to be held against outward displacement by said rod extension and to be forced forward or outward at the bottom against the resiliency of the spring.
21. The combination, in an automatic fire- 80 arm, with the main-spring, and the magazine-case, of a locking block for such case tensioned into engaging relation therewith by said spring.
22. In an automatic firearm, a plunger, a spring-pressed combined guide for said plunger and locking member for an abutment block, and an abutment block sup- 85 ported and held against downward displacement by such combined guide and locking member.
23. The combination, in an automatic fire- 90 arm, with a frame, and a spring-pressed member in said frame, of an abutment block suspended from and held against downward displacement by such member and also normally held thereby against a wall of the frame.
24. The combination, in an automatic fire- 95 arm, with a frame, of a spring-pressed member in said frame, and an abutment block mounted in the frame on such member and adapted to be rocked or swung forward at the bottom against the force of the spring-pressed member.
25. The combination, in an automatic fire- 100 arm, with a frame having an internal bearing, of an abutment block in said frame, and a spring-pressed member, also in the frame, adapted to support said block against a wall of the frame and with its head in engagement with said bearing.
26. The combination, in an automatic fire- 105 arm, with a frame having an internal bearing, of a detachable abutment block in said frame, and a spring-pressed member, also in the frame, adapted to support said block against a wall of the frame and with its head in engagement with said bearing.
27. The combination, in an automatic fire- 110 arm, with a frame having an internal bearing, of an abutment block in said frame, and a spring-pressed member, also in the frame, adapted to yieldingly support said block against a wall of the frame and with its head in engagement with said bearing.
28. The combination, in an automatic fire- 115 arm, with a slide having a bolt mounted at its rear terminal, and a second slide having a firing-pin mounted at its rear terminal, of means to check and release said bolt slide during its advance and before it arrives at the end of its forward travel, and means to 120
- 125
- 130

check and release said firing-pin slide during its advance and before it arrives at the end of its forward travel.

29. The combination, in an automatic firearm, with a slide having a bolt mounted at its rear terminal, and a second slide having a firing-pin mounted at its rear terminal, of means to check and release said bolt slide during its advance and before it arrives at the end of its forward travel, and means to check and release said firing-pin slide during its advance and before it arrives at the end of its forward travel, such means operating at different times.

15 30. The combination, in an automatic firearm, with a slide having a bolt mounted at its rear terminal, and a second slide having a firing-pin mounted at its rear terminal, of means to check and release said bolt slide during its advance and before it arrives at the end of its forward travel, and means to check and release said firing-pin slide during its advance and before it arrives at the end of its forward travel but after the interruption in the forward movement of the bolt slide has occurred.

31. In an automatic firearm, a spring-pressed and recoil-operated slide and bolt, the latter being mounted at the rear end of the former, and automatic means to check and release said slide during its advance and before it reaches the forward end of its travel.

32. In an automatic firearm, a spring-pressed recoil-operated bolt, and lock mechanism comprising a suitably mounted trigger and a pivotally connected detent, the latter being adapted to twice check and release said bolt during its advance and while the pressure of the finger upon said trigger is relaxing.

33. The combination, in an automatic firearm, with a slidingly-mounted bolt, and a slidingly-mounted firing-pin, of means to check and release said bolt twice during its advance, and means to check and release said firing-pin during its advance.

34. In an automatic firearm, a spring-pressed recoil-operated slide and bolt, a spring-pressed recoil-operated slide and firing-pin, said bolt being mounted at the rear end of its slide and said firing-pin being mounted at the rear end of its slide, automatic means for checking and releasing said bolt slide during its advance, and manually-operated means for checking and releasing said firing-pin slide during its advance.

35. The combination, in an automatic firearm, with a firing-pin slide and a bolt slide, of lock mechanism comprising a pin, a trigger piece mounted on said pin and provided at its forward terminal with an engaging and releasing dog for said firing-pin slide, and a detent having its front end pivotally connected with the corresponding end of

said trigger piece and arranged to rock on the pin at a point remote from such pivotal connection, said detent being provided at its rear terminal with an engaging and releasing dog for said bolt slide.

36. The combination, in an automatic firearm, with a firing-pin slide and a bolt slide, of lock mechanism comprising a pin, a trigger piece mounted on said pin and provided at its forward terminal with an engaging and releasing dog for said firing-pin slide, a detent having its front end pivotally connected with the corresponding end of said trigger piece and arranged to rock on said pin at a point remote from such pivotal connection, said detent being provided at its rear terminal with an engaging and releasing dog for said bolt slide, and tension means applied from below to said detent between its pivotal point of connection with the trigger piece and the pin.

37. Lock mechanism, for an automatic firearm, comprising a pin, a trigger piece mounted thereon, a detent pivotally connected at one end with the corresponding end of such piece and slotted to receive said pin upon which latter said detent oscillates, engaging and releasing members on said trigger piece and detent respectively at opposite sides of the pin, and a suitable trigger-spring.

38. The combination, in an automatic firearm, with a suitably mounted trigger piece provided with a stop, a detent pivoted to said trigger piece and provided with a hook, and suitable tension means for such parts, of a slidingly-mounted safety-catch having a hook to engage and release said detent hook and a foot to hold down and release said trigger piece stop.

39. Lock mechanism, for an automatic firearm, comprising a spring-pressed finger-operated trigger piece and a spring-pressed automatic- and finger-operated detent, the said two parts being pivotally connected at corresponding ends and both adapted to be mounted to rock on one and the same pin.

40. The combination, in an automatic firearm, with a spring-pressed recoil-operated bolt having a slide in front and a spring-pressed recoil-operated firing-pin having a slide in front said slides being provided with lock-engaging members, of a pin, a trigger piece mounted on said pin and provided with a member adapted to engage and release the lock member on the firing-pin slide, and a detent mounted to rock on said pin and provided with a member adapted to engage and release the lock member on the bolt slide, such trigger piece and detent being pivotally connected at corresponding ends.

41. The combination, in an automatic firearm, with a spring-pressed recoil-operated bolt having a slide and a spring-pressed recoil-operated firing-pin having a slide,

said bolt slide being provided with two different lock-engaging members and said firing-pin slide with a single lock-engaging member, of a suitably mounted trigger piece 5 provided with a member adapted to engage and release the lock member on the firing-pin slide, and a detent pivotally connected with said trigger piece and provided with a member adapted to engage and release both 10 of the lock members on the bolt slide.

42. The combination, in an automatic firearm, with a reciprocating bolt having ejector-engaging parts, and an extractor carried by said bolt, of a pivotally-mounted ejector bifurcated to accommodate said extractor and provided with dogs on opposite sides of its axis arranged to be acted on by the engaging parts of the bolt.

43. The combination, in an automatic firearm, with a magazine open full width at the top except at the rear where the opening is constricted to form a stop to engage the rim of a cartridge and retain the cartridge in the path of a bolt, of a spring-pressed slide having a firing-pin thereon above the rear end, a second spring-pressed slide mounted on the first and having a bolt thereon above the rear end, means to check said bolt slide long enough to allow said cartridge to clear said magazine after said bolt has advanced far enough to move the cartridge out of engagement with said stop and then to release the bolt slide, and means to check and release said firing-pin.

44. The combination, in an automatic firearm, with a magazine having a stop to engage some portion of a cartridge and retain the cartridge in the path of a bolt, of a spring-pressed bolt, means to check said bolt long enough to allow the cartridge to rise against such stop, and means to again check the bolt long enough this time to allow the cartridge to clear said magazine after the bolt has advanced far enough to move 45 the cartridge out of engagement with said stop.

45. The combination, in an automatic firearm, with a magazine having a stop arranged to retain a cartridge in the path of a bolt, 50 of a reciprocating bolt, and means to cause said bolt to advance a sufficient distance to free the cartridge from said stop and then pause before completing its forward stroke long enough for the cartridge to clear said 55 magazine.

46. Cartridge-feed-mechanism, for a firearm, of the class described, comprising a magazine provided with a cartridge stop at the open end, a spring-pressed recoil-operated bolt coacting with the magazine spring for moving a cartridge from said magazine into the firing-chamber of the arm, and means to interrupt momentarily the advance of said bolt while the cartridge is being

forced upward by the magazine spring in 65 front of the bolt and then to release the bolt.

47. Cartridge-feed-mechanism, for a firearm, of the class described, comprising a magazine provided with a cartridge stop at the open end, a spring-pressed recoil-operated bolt coacting with the magazine spring for moving a cartridge from said magazine into the firing-chamber of the arm, and means to twice interrupt the advance of said bolt to permit the cartridge to rise first 70 against said stop and second into line with said firing-chamber both times under the influence of said magazine spring.

48. The combination, in an automatic firearm, with a slide having a bolt at its rear end, of a magazine case, and a spring-pressed follower in said case having a convex cartridge-receiving top, said follower being adapted to project its convex part into the path of said bolt upon the recoil of the latter 80 after the last cartridge has left the case and been exploded.

49. The combination, in an automatic firearm, with a magazine case provided with a follower having a convex cartridge-receiving top and with a stop at the open end adapted to be contacted with by such convex part when the magazine is empty to thus limit the upward movement of said follower, of a slide having a bolt at its rear end, said convex part of the follower when in contact with said stop intersecting the path of travel of said bolt.

50. The combination, in a firearm, of a handle having an opening therethrough and 100 provided with exterior grip-retaining means and with a tongue extending from one end of said opening and adapted to engage a grip on the inside and hold it in place, and a grip fastened to said handle by the aforesaid securing means.

51. The combination, in a firearm, of a handle having an opening therethrough and provided with exterior grip-retaining means and with a resilient tongue extending from 110 one edge of said opening and adapted to engage a grip on the inside and hold it in place, and a grip releasably fastened to said handle by the aforesaid securing means.

52. The combination, in a firearm, of the 115 class described, with a magazine-chamber having its side walls cut out at the base, of a magazine-case adapted to fit such chamber and provided at the bottom with external lateral flanges countersunk within the chamber when said case is in place but exposed through the cut away portions of said walls.

53. The combination, in a firearm, with a frame having one side of its lock-chamber and one side of the chamber for the firing-mechanism open, of a removable cover for said lock-chamber and a removable cover for said firing-mechanism-chamber, the contig- 125

uous edges of the frame and covers being arranged and adapted to hold said covers in position.

54. The combination, in a firearm, with a frame having one side of its lock-chamber and one side of the chamber for the firing-mechanism open, of an upwardly-removable cover for said lock-chamber and a longitudinally-removable cover above said lock-chamber cover for said firing-mechanism-chamber, the contiguous edges of the frame and covers being arranged and adapted to hold said covers in position.

55. The combination, in a recoil-operated firearm, of the class described, with a frame having an air chamber therein, of a spring-pressed slide having a bolt mounted at the rear end thereof and arranged to reciprocate in said chamber, and a spring-pressed slide having a firing-pin mounted at the rear end thereof and arranged to reciprocate in said chamber and to operate through said bolt. 15 20
